DISPENSER

William Kappenberg, Queens Village, N. Y., assignor to Coffee Products Corporation, New York, N. Y., a corporation of New York

Application May 4, 1937, Serial No. 140,612

6 Claims. (Cl. 221—147)

This invention relates to liquid measuring or dispensing devices; and more particularly it relates to devices easily constructed and free from moving parts which dispense a predetermined quantity of liquid from a container when the container is inverted. The new devices of the invention may be easily and economically produced, and are readily fastened to bottles or other containers as by means of screw threads provided on the neck of the bottles or other containers, or in other ways, as by soldering, welding, crimping, etc., or by the use of adhesives or the like; or, the dispensing devices may be made, in part or in whole, integral with the container and as a part thereof. In some cases, where an externally applied dispensing device is not desirable, the device may be fitted within the neck of a bottle or other container, and held in place by screw threads, or friction joints, or by snap fastenings, or by constructing the device, at least in part, integrally with the container, the container being provided with an enlarged or elongated neck if desired or necessary.

The invention will be described in detail in connection with the accompanying drawing, which illustrates in a somewhat diagrammatic fashion a dispensing device which embodies the invention, but the invention is not limited thereto.

In the drawing:

30 Fig. 1 is a sectional view of the dispensing device attached to a bottle in an inverted position;

Fig. 2 is a sectional view of the same device in an upright position, showing the measured body of liquid ready to be discharged;

35 Fig. 3 is a sectional view of the same device in an inclined position showing how the liquid flows out; and

Fig. 4 is a plan view of the device.

In the drawing, there is shown a bottle 10 to which the dispensing device is attached. The dispensing device 12 as shown consists of a cylinder 14 provided with internal threads 16 at the base so it may be fastened to the bottle and with the upper end 18 closed, except for the pouring spout 17. Within this shell is a longitudinal partition 20 extending from the top 18 about half way to the bottom, this partition serving to divide the upper interior of the device into two compartments 22 and 24.

50 Above the threads 16 which permit the attachment of the device to a bottle or the like, there is provided a seat 26, on which a diaphragm or plate 28 seats. This diaphragm is provided with an opening 30 into which fits the tube 32 (the tube 32 may advantageously be integral with the dia-

phragm 28, as in the modification shown so that the device as a whole consists of but two parts). The opening 30 and the tube 32 are offset from the center of the diaphragm, so that when in place, with the member 28 seated, the tube 32 extends into the compartment 24 a short distance past the end of the partition 20. A gasket 34 of cork or other suitable material, with a properly located opening 36, is cemented to the upper face of the diaphragm 28, to provide a seal when the device is applied to a bottle or other container.

The operation of the device illustrated is very simple. Assuming that the device has been placed upon a container or bottle containing a liquid to be dispensed in predetermined portions, the bottle with the attached dispensing device is inverted, whereupon the liquid flows through the tube 32 into the compartment 24, the level of liquid rising in this compartment to a little above the end of the tube, but below the end of the partition 20, a liquid seal thus being formed which prevents any greater outflow of liquid. When the bottle or container is then placed in an upright position, part of the liquid from the chamber 24 flows back through the tube 32 and the remainder is retained in the dispensing device by the diaphragm or plate 28, as shown in Fig. 2. The relative amounts of liquid which will flow back into the bottle or container and which will be retained in the dispensing device will depend upon the relative area of the tube 32 and the cross-sectional area of the compartment 24 surrounding it; and these proportions can readily be adjusted so that with a given liquid capacity of the chamber 24 a predetermined amount of the liquid will remain in the dispensing device when the container or bottle is placed in an upright position.

When the container or bottle, with the measured amount of liquid in the attached dispensing device, is then tilted as in Fig. 3 with the spout 40 17 down, the liquid retained in the dispensing device will be poured from the spout 17. Of course, in this operation, care should be taken that the container is not tilted so suddenly as to throw some of the liquid to be dispensed into 45 the compartment 24, and also that the device is tilted sufficiently far so that the necessary liquid seal is formed. As the bottle or container is tilted and inverted to dispense the measured amount of liquid, the chamber 24 is again filled 50 to the proper depth with liquid with the result that the dispensing device is again charged with the proper amount of liquid, so that each time a portion of the liquid is dispensed, another equal portion is charged to the dispensing device. 55

The amount of liquid to be dispensed in each portion by one of these improved devices may be varied widely, as by varying the length of the tube 32, or the diameter of the cylinder 14 or the 5 relative cross-sectional area of the tube 32 and the compartment 24, etc. For example, by providing the tube 32 with an inner sliding sleeve, the dispensing device may readily be made adjustable, so that it can be adjusted, within reasonable 10 limits, to dispense various amounts of liquid in measured portions. Or the device may be made adjustable by positioning the seat 26 somewhat further in the shell 14 and providing removable rings seated thereon, so that the position of the diaphragm or plate 28 and the tube 32 may be varied with respect to the partition 20. However, it should be noted that in all cases it is essential that the tube 32 extend past the 15 end of the partition 20 so that necessary liquid seal is formed in the chamber 24. Also, it should be noted that it is essential that the partition 20 does not extend too far towards the bottom of the dispensing device, or some of the liquid to be dispensed will pass into the chamber 24 when 20 the container with the attached dispensing device is tilted.

A device adjusted for the dispensing of a liquid in measured quantities of about 5 cc., having a construction such as illustrated in the drawing, may have about the following dimensions:

- 30 Inner diameter of cylinder 14, 1 inch.
- Length of partition 20, 1 $\frac{1}{2}$ inches.
- Distance from center line of cylinder to partition 20, $\frac{3}{2}$ inch.
- 35 Overall length from tip of spout, 3 inches.
- Overall length along elements opposite spout, $2\frac{1}{8}$ inches.
- Distance from bottom of device to seat 26, $\frac{7}{8}$ inch.
- 40 Inner diameter of tube 32, $\frac{5}{16}$ inch.
- Length of tube 32, measured from under side of diaphragm 28, $1\frac{1}{8}$ inches.
- Thickness of tube 32 and diaphragm 28, $\frac{1}{16}$ inch.
- 45 It will be understood that the above dimensions are given for a device intended to dispense approximately 5 cc. of liquid in each operation and that certain slight adjustments of the dimensions will be required to provide the necessary taper for the withdrawal of the molds used in casting, if the parts are to be cast.

The device illustrated is of very simple construction, such that the parts may be readily made of brass, aluminum, "plaskons", resins, 55 waxes, or other suitable material and are such that no expensive or intricate machine work is required for their production, simple casting, molding, stamping, pressing, drawing or spinning operations being sufficient; the selection of the 60 particular method of fabrication depending, of course, on the type of material selected, etc.

The invention is capable of many practical embodiments, one of which has been described in detail, as will be apparent to those skilled 65 in the art. For example, instead of fastening the device to a container by internal or external screw threads, it may be fastened by a friction fit, for which a suitable gasket may be provided; or the container may be provided with a rim 70 or the like at the top, on which a disc, to serve as the diaphragm, fits, a specially constructed cap being provided of such design as to complete the dispensing device; or, in making bottles or the like, the diaphragm and the tube therethrough 75 may be molded within the neck, and a cap hav-

ing a partition extending at right angles to the plane of the cap may be provided, which, when attached to the bottle or the like, completes the dispensing device; or, the neck of the bottle itself may serve as the inner tube, with the dispensing device of enlarged diameter to fit over the neck so that the neck extends into the proper inner compartment of the device. The new dispensing devices are not only useful for attachment or use with bottles and similar containers, but also for use with paper or cardboard cartons, cans, etc., in which case they may advantageously be constructed integrally with the container, either externally or internally, when the containers are manufactured, as by forming them of cardboard, tin, waxed paper, etc., held in place by crimping, beading, clipping, pinching, etc., or by adhesives.

While the dispensing devices have been described with particular reference to the dispensing of liquids in measured and predetermined portions, it is also applicable to the similar dispensing of such solid granular materials as sugar, salt, etc.

I claim:

1. A dispensing device adapted to dispense liquids or pourable solids in predetermined portions comprising a cylindrical chamber adapted to be fastened to a container, a longitudinal partition in the upper portion of said chamber dividing said upper portion into two compartments, a tube communicating with the bottle or container extending past the end of said partition into one of said compartments, and a diaphragm through which said tube passes separating the interior of said device from the interior of the container to which it is attached.

2. A dispensing device adapted to dispense liquids or pourable solids in predetermined portions comprising a cylindrical chamber adapted to be fastened to a container, a longitudinal partition in the upper portion of said chamber dividing said upper portion into two compartments, a tube communicating with the bottle or container extending past the end of said partition into one of said compartments, an opening or spout at the top of the other of said compartments, and a diaphragm through which said tube passes separating the interior of said device from the interior of the container to which it is attached.

3. A dispensing device adapted to dispense liquids and pourable solids in predetermined portions comprising a cylinder with top and bottom walls, a longitudinal inner partition dividing the upper portion of said cylinder into two compartments, a tube opening through the bottom wall and extending a short distance past the end of said partition into one of said compartments, and an opening or spout in the other compartment through which the liquid or pourable solid may be dispensed.

4. A dispensing device adapted to dispense liquids and pourable solids in predetermined portions comprising a cylinder with top and bottom walls, a longitudinal inner partition extending from the top wall about halfway to the bottom wall and dividing the upper portion of said cylinder into two compartments, a tube opening through the bottom wall and extending a short distance past the end of said partition into one of said compartments, and an opening or spout in the other compartment through which the liquid or pourable solid may be dispensed.

5. A dispensing device adapted to dispense liquid or pourable solids from a container in pre-
